F. X. MALOCSSAY

CIGAR BAND PERFORATING AND CRIMPING MECHANISM

Filed Sept. 15, 1920

Francis X. Malocsay
BY his ATTORNEY
John L. Levy

INVENTOR

UNITED STATES PATENT OFFICE.

FRANCIS X. MALOCSSAY, OF NEW YORK, N. Y., ASSIGNOR TO INTERNATIONAL BANDING MACHINE COMPANY, OF NEW YORK, N. Y., A CORPORATION OF NEW YORK.

CIGAR-BAND PERFORATING AND CRIMPING MECHANISM.

Application filed September 15, 1920. Serial No. 410,433.

This invention relates to a mechanism which may be in the nature of an attachment to be applied to cigar banding machines or may be used independently thereof, as desired, and the object of this invention is to provide a mechanism which will perforate cigar bands, and produce by means of such perforation, a small projecting tab known as a "tear-off" tab by means of which the cigar band may be readily torn off or removed from a cigar.

A further object of this invention is to produce a means of crimping or bending one end of a cigar band so that when said band is fed to mechanism which folds it in position about a cigar, the crimped or bent end of the band will more readily follow the contour of the cigar and find its proper position thereon.

A further object of this invention is to provide the mechanism above described which can be attached to practically any form of cigar band applying machine and utilized on such machine without decreasing the speed thereof.

With these objects and other objects which may hereinafter appear in view, I have devised the particular arrangements of parts hereinafter set forth and more particularly pointed out in the claims appended hereto.

Reference is to be had to the accompanying drawing forming a part hereof in which—

Figure 1 is a plan view of my improved band perforating and crimping mechanism.

Figure 2 is a sectional view of the same on the line 2—2 of Figure 1 looking in the direction of the arrows.

Figure 3 is a sectional view on the line 3—3 of Figure 1 looking in the direction of the arrows.

Figure 4 is a perspective view of one of the jaws or die members.

Figure 5 is a plan view of one of the cigar bands after the same has been perforated and folded.

Figure 6 is a sectional view of the same on the line 6—6 of Figure 5 looking in the direction of the arrows.

Throughout the various views of the drawings similar reference characters designate similar parts. In the preferred em-

bodiment of my invention as disclosed in the accompanying drawing, 1 indicates one of the cigar bands to be perforated and crimped or bent. In the present forms of cigar banding machine, these bands are usually carried in a holder or stack from which they are removed successively by means of a reciprocating conveyor, a portion of which is indicated at 2. The conveyor 2 is usually provided with suction passages terminating in openings as indicated at 3 which are usually situated at one end of the conveyor. By means of suitable mechanism, suction is exerted through these passages and the suction tends to hold one of these cigar bands on the conveyor. The band is usually carried upon the conveyor face upward and at 4 is indicated the gummed end of the band. The conveyor is operated so that it pauses momentarily at the perforating and crimping mechanism which acts upon the ungummed end 5 of the band while the gummed end 4 is moistened by mechanism now to be described.

The moistening mechanism is preferably in the form of a reciprocating plunger 11, the upper end of which is provided with a moistened pad or strip of absorbent material 12. The plunger 11 moves upwardly and contacts with the gummed surface of the band at 4 to moisten the gum thereon. Above the plunger 11 is provided an abutment 10 which is in the form of a block of rubber or like resilient material. The abutment 10 is preferably carried in a pair of clamping jaws 9 mounted upon a bracket 8 secured to the machine.

While the moistening operation is taking place at the gummed end 4 of the band, the ungummed end 5 is being acted upon by the perforating and crimping mechanism now to be described.

At 13 is shown the upper jaw of the crimping and perforating mechanism said jaw being provided with a downwardly projecting lug 24.

At 14 is shown the lower jaw which has a pair of spaced-apart ears 15 having perforations 16 through which passes a pin 17 to pivotally secure the jaw 14 to the lug 24 on the upper jaw 13. It will be seen that both of the jaws 13 and 14 are kept normally

separated by means of a coil spring 22 which seats in a recess 21 in the lower jaw 14 and in a recess 25 in the upper jaw 13.

The crimping or bending mechanism which is intended to produce the downwardly bent end 6 on the band comprises a pair of co-operating dies 19 and 20. The lower die 19 is a male die and is mounted in a transversely extending slot or groove 18 in the jaw 14. The upper die 20 is a female die and is mounted in a transversely extending slot or groove in the upper jaw 13. At 23 is a suitable push rod which is vertically reciprocated by means of cam mechanism on the machine. It will be seen that by an upward movement of the push rod 23, the dies 19 and 20 are brought together by the closing of the jaws 13 and 14 and the end of the band is provided with a transverse crease which produces the downwardly bent portion 6 disclosed in Figures 5 and 6.

When the bands are folded about a cigar either by hand or by suitable mechanism, the ungummed end 5 of the band is the first end to be folded in position. In order to aid the end 5 in following the substantially cylindrical contour of the cigar, the downwardly bent end 6 is desirable.

By means of the arrangement above described this crimping or bending of one end of the band out of the general plane of the cigar band is expeditiously produced. At 26 is shown one of the die members which produce the projecting "tear-off" tab. This die member 26 is situated upon the upper face of the jaw 14 and the upper surface 27 of this die member 26 is preferably inclined for a purpose to be hereinafter set forth. To produce the projecting tab 7, the die 26 which is the lower die, co-operates with an upper die member 28 which is mounted to move vertically in a guide 29 in the jaw 13. The die member 28 is spring-pressed by means of a spring finger 30 secured to a block 31 by the screw 32.

From the foregoing the operation of my improved perforating and crimping mechanism will be readily understood. The band 1 is carried upon the conveyor 2 to the moistening mechanism and momentarily pauses at that point to permit its gummed end 4 to be moistened as hereinbefore described. The perforating and crimping mechanism simultaneously acts upon the ungummed end 5 of the band. By an upward movement of the push rod 23 the jaws 13 and 14 are brought together which bring the crimping jaws 19 and 20 together as well as the perforating dies 26 and 28.

The inclined surface 27 of the die 26 together with the resilient mounting of the upper die 28 produces a U-shaped slit in the band and causes the tab 7 to project or protrude above the surface of the band. After this operation has been performed, the jaws

13 and 14 are spread apart permitting the band to be moved from between them by the conveyor 2 which carries the band to the mechanism which folds it about a cigar.

It will be obvious that the provision of my improved perforating and crimping mechanism upon a cigar banding machine in no way decreases its speed due to the fact that in these machines the conveyor momentarily makes a pause at the moistening mechanism and the crimping and perforating operation takes place during that pause.

It will be understood that either the crimping of the band or the producing of the "tear-off" tab may be done independently, by the removal of either pair of dies.

From the foregoing, it will be obvious that my invention is not to be restricted to the exact embodiment shown but is broad enough to cover all structures coming within the scope of the annexed claims.

Having described my invention, what I claim is:—

1. A device of the character described, comprising coacting means for simultaneously crimping and tabbing one end of a cigar band, and means for causing operation of said coacting means.

2. In a device of the character described, the combination of means for conveying a cigar band, means for supporting said band when in operative position, and means comprising a pair of coacting dies adapted to receive and to cut into said band a tab or lip.

3. In a device of the character described, the combination of a band supporting conveyor, a pair of coacting dies having suitable cutting and crimping elements whereby one end of the band will be simultaneously crimped and tabbed when inserted between and acted upon by said dies, and means for causing said dies to so coact.

4. A device of the character described, comprising a pair of pivoted jaws, co-operating dies on said jaws for engaging a cigar band adjacent one of its ends, said dies having elements for simultaneously folding said end and cutting a tab in said band adjoining said fold.

5. A device of the character described, comprising a pair of pivotally connected jaws, one of said jaws having a die with an inclined face, a resiliently mounted die on the other jaw co-operating with the first mentioned die, said dies being provided with elements for simultaneously producing a fold in the end of a band and a tab adjacent thereto.

6. In a cigar banding machine, a band moistener, a band crimper, and a conveyor for engaging a cigar band and presenting the same simultaneously to said moistener and said crimper.

7. In a cigar banding machine, a band

moistener, a band crimper spaced-apart therefrom, and a conveyor, operating between said moistener and said crimper, adapted to engage a band and present the same simultaneously to said moistener and said crimper.

8. In a cigar banding machine, band moistening means, band crimping means spaced from said moistening means a distance suffi-

10 cient to permit a flat cigar band to extend with one end operatively positioned relative to said moistening means and the other end operatively positioned relative to said crimping means, and a conveyor operating 15 between said moistening means and said crimping means adapted to engage the central portion of said band and present its ends simultaneously to said moistening and said crimping means.

20 9. In a cigar banding machine, a band moistener, a band tab cutter spaced apart therefrom, and a conveyor operating between said moistener and said cutter adapted to present a band simultaneously to said

25 moistener and said cutter.

10. In a cigar banding machine, means for moistening one end of a band, means for producing a tab at the other end of the band, said moistening and tabbing means being spaced apart and a band conveyor operating between said moistening and said tab producing means to simultaneously present the ends of said band to said moistening and said tab producing means.

11. In a cigar banding machine, band moistening means, band tab producing means spaced from said moistening means a distance sufficient to permit a flat cigar band to extend with one end operatively positioned relative to said moistening means and the other end operatively positioned relative to said tab producing means, and a conveyor operating between said moistening means and said tab producing means to simultaneously present the ends of said band to said moistening means and said tab producing means.

Signed at the city, county and State of New York this 2nd day of September, 1920.

FRANCIS X. MALOCSAY.
